109,429

DESIGN FOR A BOOT

Robert Sieburth, Concord, Mass.

Application March 16, 1938, Serial No. 75,852

Term of patent 3½ years

To all whom it may concern:

Be it known that I, Robert Sieburth, a citizen of Germany, residing at Concord, in the county of Middlesex and Commonwealth of Massachusetts, have invented a new, original, and ornamental Design for a Boot, of which the following is a specification reference being had to the accompanying drawing, forming a part thereof.

I claim:

The ornamental design for a boot as shown.

ROBERT SIEBURTH.
